Fig. 6

Fig. 7

Fig. 8

FIG. 1 is a perspective view of a first embodiment of a lightweight headset showing our new design;

FIG. 2 is a front elevational view of the first embodiment;

FIG. 3 is a side elevational view of the first embodiment;

FIG. 4 is a rear elevational view of the first embodiment;

FIG. 5 is a perspective view of a second embodiment of the lightweight headset shown in FIG. 1;

FIG. 6 is a front view of the second embodiment;

FIG. 7 is a side view of the second embodiment; and

FIG. 8 is an end view as seen from below in FIG. 7.

We claim:

The ornamental design for a lightweight headset, substantially as shown and described.
